UNITED STATES PATENT OFFICE.

TAYLOR W. FERRELL AND WALT BLOESER, OF CHICAGO, ILLINOIS, ASSIGNORS TO THE KINGSLEY-MILLER COMPANY, OF CHICAGO, ILLINOIS, A CORPORATION OF ILLINOIS.

DESIGN FOR A RADIATOR CAP.

Application filed September 13, 1926. Serial No. 19,055. Term of patent 14 years.

To all whom it may concern:

Be it known that we, TAYLOR W. FERRELL and WALT BLOESER, both citizens of the United States, and both residing at the city of Chicago, in the county of Cook and State of Illinois, have jointly invented a new, original, and ornamental Design for Radiator Caps, of which the following is a specification, reference being had to the accompanying drawing, forming part hereof.

In this drawing:

Figure 1 is a front elevation of the radiator cap;

Figure 2 is a plan view of the cap; and
Figure 3 is a rear elevation of the cap.

We claim:

The ornamental design for a radiator cap, as shown.

TAYLOR W. FERRELL.
WALT BLOESER.
